EAVESTROUGH SCOOP

Roman Lieber, Royal Oak, Mich.

Application May 29, 1956, Serial No. 41,698

Term of patent 14 years

(Cl. D9—6)

Fig. 1 is a side elevational view of an eavestrough scoop embodying my new design;

Fig. 2 is a fragmentary view thereof; and

Fig. 3 is an end elevation taken from the right side of Fig. 1, and being reduced in scale.

The portions shown broken away in the several views represent indeterminate length.

I claim:

The ornamental design for an eavestrough scoop, substantially as shown and described.
